UNITED STATES PATENT OFFICE.

JULIUS BRENZINGER, OF FAIRFIELD, CONNECTICUT, ASSIGNOR TO SANITARY CAN MACHINERY COMPANY, OF ELLSWORTH, MAINE, A CORPORATION OF MAINE.

NON-CIRCULAR-CAN-COVER-LINING MACHINE.

1,347,483.

Specification of Letters Patent.

Patented July 20, 1920.

Application filed August 9, 1918. Serial No. 249,105.

To all whom it may concern:

Be it known that I, JULIUS BRENZINGER, a citizen of the United States, residing at Fairfield, in the county of Fairfield and 5 State of Connecticut, have invented certain new and useful Improvements in Non-Circular-Can-Cover-Lining Machines, of which the following is a specification.

In connection with covering and sealing 10 sheet-metal containers, commonly known as "tin cans," by what is known as the "seaming" or "double-seaming" process, it has been found necessary to provide a suitable packing between the layers of metal which are 15 intercurled and compressed to form the seam, and this packing is usually provided in the form of a self-solidifying liquid compound which is deposited along the edge of the cover to constitute an adhering gasket. 20 In more common types of present machines, the liquid is delivered upon the cover-edge from a suitable dispensing nozzle, the cover being rotated or otherwise moved to present the entire edge thereof progressively to said 25 nozzle—a process which doubtless may be said to be fairly satisfactory when round covers are being lined, but which presents more serious difficulties in connection with non-circular—such as oblong or so-called 30 "square"—can covers.

The present invention relates generally to machines for applying this liquid lining compound to can covers, with more particular reference to non-circular or so-called 35 "square" covers, and has in view the provision of a comparatively simple machine, and one which will not only be efficacious and dependable but which may be successfully operated at comparatively high speed.

40 My invention will be more readily understood by reference to the accompanying drawings, forming a part of this specification, in which I have illustrated a practical and convenient embodiment thereof, and in 45 which—

Figure 1 is a top plan view, partly in section;

Fig. 2 is a transverse vertical section, taken substantially on the line 2—2 of Fig. 50 1, and

Fig. 3 is a fragmentary sectional view similar to Fig. 2, showing the cover and its support in a different position.

Referring now to the drawings in detail, 55 numeral 5 designates a suitable supporting

frame or table-top on which are mounted the standards 6 6 in which is journaled the shaft 7. I have shown this shaft 7 as hollow, whereby steam or other hot fluid may be passed therethrough, the ends of the shaft 60 being threaded for the reception of plugs 8 8 having longitudinal bores 9 and which provide connections for the tubes 10 10 leading from any suitable source or sources of steam or hot-fluid supply. I have shown 65 this shaft driven from a pulley 11 mounted thereon which is designed to be connected in the usual manner with a main driving element.

Mounted on the shaft 7 is the wheel 12, 70 and as it is necessary to retain many kinds of lining compounds in a heated condition until final application thereof to the cover, I have shown this wheel as hollow, providing a chamber 13 into which steam or other 75 hot fluid may be directed from the shaft 7 and thus heat said wheel and any substance adhering thereto. The wheel 12 is also preferably provided with a rounded periphery 14 for a purpose which will subsequently be 80 made clear.

Supported from the table-top or base 5 by brackets 15 15 is the open tank 16, adapted to contain a suitable liquid or semi-liquid lining compound 17, and this tank is so positioned with relation to the wheel 12 that the lower side of the latter dips into the liquid 17 when a suitable quantity thereof is placed or remains in the tank. Obviously, a thin film or coating of the liquid will adhere to 90 the periphery of the wheel as the latter is revolved by the shaft 7.

Non-circular cans are generally either square or oblong, so-called, in lateral contour, with substantially rounded corners, 95 and the covers or ends therefor, of course, are of corresponding configuration. Relatively little difficulty is encountered in attempting to apply a seam-packing peripheral lining to round covers. It is only necessary, in general, to establish relative rotary movement between the cover and a discharge nozzle or other form of dispensing device. When the cover is not round, however, pure rotary movement will obviously not suffice, 105 and in the lining operation movement of either the dispensing device or the cover must be positively guided in a deviating or deflecting—although regular or symmetrical—path. The difficulties to be overcome in 110

attempting to so move and guide a regulable dispensing device will be apparent, and while of less degree in connection with attempts to so move and guide the cover, it must be borne in mind that cans are made in many different sizes, each size of can requiring an end or cover of corresponding dimensions, and a cover-lining machine should be quickly and readily adapted and adjusted 10 for covers for cans of any of the various standard sizes. This necessitates the provision not only of means for insuring positively guided regularly-deviating movement of the cover and its support, but also of 15 means for this purpose which are capable of quick and ready manipulation and adjustment, by way of substitution of parts or otherwise, to vary either the course of the path, or the area of the surface circumscribed thereby, or both thereof.

In the embodiment of my invention herein shown and described, I present the edge of the cover to the coated periphery of the wheel 12, and it will be apparent that by 25 pressing said cover edgewise against the wheel, upon revolution of both the wheel and the cover, in intersecting planes, what may be termed a linear portion of the coating will be scraped from the wheel and be deposited along the cover-edge—or in the peripheral groove or gutter usually provided at the cover-edge for this and other purposes. If the cover is circular, it will be apparent that simple rotation thereof, the edge 30 being held against the periphery of the revolving wheel, will result in the depositing along the cover-edge—or in the peripheral groove or gutter to which I have referred—coalescing layers of the semi-liquid and 35 slightly viscous compound which, upon drying or hardening to a greater or lesser degree, form what is termed the "lining skin" which serves as a hermetic gasket or seam-packing when the cover is seamed or otherwise secured to the body portion of the container.

This liquid composition may obviously be similarly applied to the edge of a non-circular cover provided movement of the latter 40 with respect to the periphery of the revolving wheel is so controlled and directed as to maintain at all times continuous contact between the shifting cover-edge and the wheel. To effect such control and direction, I have 45 shown a lever-arm 18 pivoted at one end on the stud 19 on the upper face of the table-top or base 5 and thus being adapted to oscillate toward and away from the wheel 12. Intermediate the ends of the lever-arm 18 50 is journaled the short shaft 20, the lower end of which swings clear of the table-top 5.

At the upper end of the shaft 20 is mounted the chuck 24, the horizontal or lateral contour of which corresponds to that of the 60 cover 25—which for the purposes of this

description I have shown as oblong—but the dimensions of which are slightly less than those of the cover in order that the chuck may enter the inverted dish-shaped depression provided when the off-set flange 26 is 70 formed in the usual manner at the edge of the cover, whereby the cover is laterally supported against the forces of the lining operation.

Journaled in the table-top or base 5 is the 75 vertical shaft 27, at the upper end of which is mounted the roller 28 against which impinges a cam 29 mounted on the shaft 20. As this cam 29 is to control oscillating movement of the lever-arm 18 to retain the cover-edge in contact with the periphery of the wheel 12 during rotation of the cover-carrying chuck 24, it will be apparent that, first, the contour of the cam must correspond to that of the chuck—that is, to that of the can 80 cover, which amounts to the same thing—and, second, that the contour of the periphery of the roller 28 must correspond to the cross-sectional contour of the periphery 85 of the wheel 12, the curvature being of corresponding degree—that is to say, if the periphery of the wheel is circular in cross-sectional contour, the diameter of the circle and the diameter of the roller 28 should be the 90 same. It will now be apparent that if the shaft 20 is rotated, with the cam 29 yieldingly pressed against the roller 28, the lever-arm 18 will be oscillated and the chuck-supported cover 25 rotated with the edge thereof of continuously in contact with the coated 95 periphery of the wheel 12.

To rotate the shaft 20 around a regularly shifting axis, I mount upon the shaft 27, preferably below the roller 28, a pinion 30 with the teeth of which mesh the teeth of a 100 gear 31 on the shaft 20 below the cam 29. The contour of the gear 31 also corresponds to that of the chuck 24 and the chuck-supported cover 25, and it will be noted that the 105 path of travel of the cover edge is directed and controlled by the cam 29 and not by the gear 31. In the latter case, either the gear-teeth would have to be cut with such mathematical precision as to render excessive the 110 cost of production, or all forces tending to move the arm 18 toward the wheel 12 would be opposed only by contact between the wheel and the edge of the cover, and except with extraordinary nicety of adjustment the 115 tendency would be to tilt the cover and dislodge the same from the chuck 24; or, should any form of cover retaining means be provided above the chuck, to prevent such dislodgment, the tilting forces would generate friction which would more or less seriously 120 impede rotary movement of the cover.

It is best, of course, to provide such cover retaining means, which must obviously be of such character as to interfere to the least 130

possible extent with the manual operation of positioning a cover on the chuck and that of removing from said chuck a lined cover. For this purpose, I have shown an arm or 5 bracket 32 mounted on the lever-arm 18 and projecting over the chuck 24. At the free end of this arm 32 I slidably mount a loose rod or stem 33 yieldingly pressed downwardly by the coil-spring 34. At the lower 10 end of the rod or stem 33 is mounted what may be termed a presser-shoe 35 adapted to impinge against the top face of the can cover 25 and yieldingly press said cover against the chuck 24. The lower face of 15 this presser-shoe 35 is curved or convex, as shown, in order that a cover may be readily slipped thereunder for the lining operation and removed from the chuck thereafter, the spring 34 yielding readily to the manual 20 forces exerted in positioning and removing the covers, but the power thereof being sufficient to overcome the frictional tilting forces of the wheel 12.

I have shown the lever-arm 18 yieldingly 25 pressed in the direction of the wheel 12 by means of a spring 36 in tension between said arm and a hook 37 or other suitable anchorage on the table-top or base 5.

The shaft 27 may be driven in any suitable 30 manner, either from the shaft 7 or directly from the source of power through the interposition of any common and well-known power-transmitting instrumentalities, such as a gear-train or a chain and 35 sprocket, this being so obvious an expedient that I have considered it unnecessary to illustrate the same in the drawings.

In order to prevent the adhesion of an excess of liquid material to the periphery of 40 the wheel 12, and to make more uniform the film or coating thereon, I mount upon the side of the tank 16 a scraper 38, the configuration of the edge of which corresponds to that of the periphery of said wheel. It 45 is, of course, desirable that a substantially thin and uniform layer of the liquid lining compound be carried by said wheel to the cover edge, and proper relative positioning of this scraper 38 will insure such uniformity and the desired volume, the excess or 50 surplus material being directed back into the tank.

Covers or ends for "tin cans" designed to be hermetically sealed are now almost invariably provided with off-set flanges, and the flange-edge is oftentimes longitudinally curled or bent—primarily for the purpose of preventing nesting of the covers when stacked, so that each may be readily fed 55 from the bottom of a stack thereof either for the lining or the seaming operation, or both thereof, but possibly also for the purpose of forming a groove or gutter 39 for the reception and retention of the lining 60 compound when applied in liquid form, par-

ticularly if the latter is delivered to the cover from a dispensing spout or nozzle. In so-called round covers, this groove or gutter is continuous, but in connection with oblong or so-called "square" covers I have found it 70 preferable to curve or bend the flange on two opposite sides only of the cover, as and for the reasons clearly set forth in an earlier Patent, No. 1,296,474, granted to me March 4, 1919. Proper size and contour of the cam 75 29, however, will insure the effective presentation of the curled edge of the cover, as shown in Fig. 2, and also the flat or uncircled edge thereof, as shown in Fig. 3, which is also illustrative of operation in connection with a continuously flat flange.

From the foregoing, it will doubtless be apparent that I have provided a machine of exceedingly simple construction and operation by means of which non-circular can 85 covers may be readily, efficaciously and dependably lined.

Many modifications of minor details of my improved non-circular can cover lining machine will doubtless readily suggest themselves to those skilled in the art to which it appertains, and I therefore do not desire to limit my invention to the specific construction herein shown and described.

I claim as new and desire to secure by Letters Patent:

1. In a machine of the character described, the combination of a rotating element having a smooth face adapted to receive a liquid coating, means for supporting a can head or cover in edgewise disposition relative to said face, and means for rotating said supporting means, said element and said supporting means being relatively shiftable toward and away from each other during rotation thereof.

2. In a machine of the character described, the combination of a rotating element having a smooth face adapted to receive a liquid coating, means for supporting a can head or cover in edgewise disposition relative to said face, and means for rotating said supporting means, the latter being shiftable toward and away from said element during rotation thereof.

3. In a machine of the character described, the combination of a rotating element having a smooth face adapted to receive a liquid coating, means for supporting a can head or cover in edgewise disposition relative to said face, and means for rotating said supporting means, said element and said supporting means being relatively shiftable toward and away from each other during rotation thereof and spring- 120 pressed in the direction of each other.

4. In a machine of the character described, the combination of a rotating element having a smooth face adapted to receive a liquid coating, means for support-

ing a can head or cover in edgewise disposition relative to said face, and means for rotating said supporting means, the latter being shiftable toward and away from said element during rotation thereof and spring-
5 pressed toward said element.

5. In a machine of the character de-
scribed, the combination of a rotating ele-
10 ment having a smooth face adapted to re-
ceive a liquid coating, means for support-
ing a can head or cover in edgewise dis-
position relative to said face, means for
rotating said supporting means, and means
15 for relatively shifting said element and said
supporting means toward and away from
each other during rotation thereof.

6. In a machine of the character de-
scribed, the combination of a rotating ele-
20 ment having a smooth face adapted to re-
ceive a liquid coating, means for support-
ing a can head or cover in edgewise dis-
position relative to said face, means for
rotating said supporting means, and means
25 for shifting said supporting means toward
and away from said element during rotation
thereof.

7. In a machine of the character de-
scribed, the combination of a rotating ele-
30 ment having a smooth face adapted to re-
ceive a liquid coating, means for support-
ing a can head or cover in edgewise dis-
position relative to said face, means for rot-
ating said supporting means, positive means
35 for relatively shifting said element and said
supporting means away from each other and
yielding means for relatively shifting the
same toward each other during rotation
thereof.

8. In a machine of the character de-
40 scribed, the combination of a rotating ele-
ment having a smooth face adapted to re-
ceive a liquid coating, means for support-
ing a can head or cover in edgewise dis-
position relative to said face, means for rot-
45 ating said supporting means, positive means
for shifting said supporting means away
from said element and yielding means for
shifting the same toward said element dur-
ing rotation thereof.

50 9. In a machine of the character de-
scribed, the combination, with a rotatable
element having a smooth face adapted to re-
ceive a liquid coating, a rotatable non-cir-
55 cular chuck for supporting a can head of
corresponding contour in edgewise dis-
position relative to the coated face of said ele-
ment, a reciprocating carriage for said
chuck, a driving pinion, and a chuck-rotat-
ing gear on said carriage in mesh with said

pinion, the general peripheral contour of 60
said gear corresponding to that of said
chuck.

10. In a machine of the character de-
scribed, the combination, with a rotatable
element having a smooth face adapted to re- 65
ceive a liquid coating, a rotatable non-cir-
circular chuck for supporting a can head of
corresponding contour in edgewise disposi-
tion relative to the coated face of said ele-
ment, a reciprocating carriage for said 70
chuck, a driving pinion, a chuck-rotating
gear on said carriage in mesh with said
pinion, the general peripheral contour of
said gear corresponding to that of said
chuck, and means yieldingly pressing said 75
carriage in the direction of said element.

11. In a machine of the character de-
scribed, the combination, with a tank
adapted to contain a liquid compound, and
a roller adapted to dip into the liquid in 80
said tank, said roller having a transversely
circular peripheral face, of a rotatable non-
circular chuck for supporting a can head
of corresponding contour in edgewise dis-
position relative to the coated face of said 85
roller, a reciprocating carriage for said
chuck, a driving pinion of the same mean
diameter as the diameter of the transverse
circle of the roller periphery, and a chuck-
rotating gear on said carriage in mesh with 90
said pinion, the general peripheral con-
tour of said gear corresponding with that
of said chuck.

12. In a machine of the character de-
scribed, the combination, with a tank 95
adapted to contain a liquid compound, and
a roller adapted to dip into the liquid in
said tank, of a rotatable non-circular chuck
for supporting a can head of corresponding
contour in edgewise disposition relative to 100
the coated periphery of said roller, a recip-
rocating carriage for said chuck, a driving
pinion, said roller having a transversely
circular peripheral face of the same diam-
eter as the mean diameter of said pinion, a 105
chuck-rotating gear on said carriage in
mesh with said pinion, the general periph-
eral contour of said gear corresponding to
that of said chuck, and means yieldingly
pressing said carriage in the direction of 110
said roller.

In testimony of the foregoing, I have
hereunto set my hand in the presence of two
witnesses.

JULIUS BRENZINGER.
